UNITED STATES PATENT OFFICE

156,482

TRANSFORMER FOR TOY RAILROADS

Joseph L. Bonanno, Madison, N. J., assignor to
The Lionel Corporation, New York, N. Y., a cor-
poration of New York

Application July 6, 1949, Serial No. 3,737

Term of patent 14 years

(Cl. D26—1)

To all whom it may concern:

Be it known that I, Joseph L. Bonanno, a citizen of the United States of America, and a resident of Madison, in the county of Morris and State of New Jersey, have invented a new, original, and ornamental Design for a Transformer for Toy Railroads, of which the following is a specification, reference being had to the accompanying drawing, forming a part thereof.

In this drawing:

Figure 1 is a top plan view of a transformer for toy railroads showing my new design;

Figure 2 is a side elevational view thereof;
and

Figure 3 is an end elevational view.

I claim:

The ornamental design for a transformer for toy railroads, as shown.

JOSEPH L. BONANNO.
